UNITED STATES PATENT OFFICE.

EDWIN H. GREEN, OF ST. LOUIS, MISSOURI.

DESIGN FOR A MUSTACHE-GUARD FOR CUPS.

SPECIFICATION forming part of Design No. 29,466, dated October 11, 1898.

Application filed September 6, 1898. Serial No. 690,372. Term of patent 7 years.

To all whom it may concern:

Be it known that I, EDWIN H. GREEN, of the city of St. Louis, State of Missouri, have invented and produced a new and original Design for Mustache-Guards for Cups, of which the following is a full, clear, and exact description, reference being had to the accompanying drawings, forming a part thereof.

Figure 1 is a plan view of a mustache-guard embodying my design. Fig. 2 is a front elevation of the mustache-guard seen in Fig. 1.

As shown in the drawings, the leading or material feature of my design consists of a segmental plate 1, slightly curved in cross-section, which plate is provided with the transversely-arranged corrugations 2, which terminate at the outer edge of the plate in

the scallops 3. The inner edge of the plate is provided with the rib 4, and at each end of said rib is a downwardly-pending tongue 5, and adjacent each of said tongues near the outer edge of the plate is a downwardly-pending tongue 6. The lower ends of these tongues 5 and 6 may be ornamented with a plurality of lugs 7. 25

I claim—

The design for a mustache-guard for cups, substantially as herein shown and described.

In testimony whereof I affix my signature in presence of two witnesses.

EDWIN H. GREEN.

Witnesses:

M. P. SMITH,

JOHN C. HIGDON.
